US00D622214S

(12) **United States Design Patent**
Thorsteinsson et al.

(10) **Patent No.:** US D622,214 S
(45) **Date of Patent:** ** Aug. 24, 2010

(54) **ELECTRICAL TRANSFORMER**

(75) Inventors: **Sigurdur Thorsteinsson**, Milan (IT);
Egil Stryken, Solbergelva (NO);
Richard Tinggren, Thalwil (CH)

(73) Assignee: **ABB Technology AG**, Zurich (CH)

(**) Term: **14 Years**

(21) Appl. No.: **29/356,632**

(22) Filed: **Mar. 1, 2010**

Related U.S. Application Data

(62) Division of application No. 29/336,557, filed on May 5, 2009, now Pat. No. Des. 613,687, which is a division of application No. 29/317,370, filed on Apr. 29, 2008, now Pat. No. Des. 594,408, which is a division of application No. 29/282,093, filed on Jul. 11, 2007, now Pat. No. Des. 570,282, which is a division of application No. 29/275,256, filed on Dec. 19, 2006, now Pat. No. Des. 550,155, which is a division of application No. 29/204,775, filed on May 5, 2004, now Pat. No. Des. 542,734.
